[57] ABSTRACT

A three-dimensional mannequin structure having a unique costume arrangement disposed thereon for use in photography applications. The mannequin structure is similar to a conventional full-body adult-size mannequin as is commonly employed for displaying wearing apparel with the principal exceptions that it has no head, neck, or arms, and the major portion of the back thereof, extending from the top of the shoulders to the calf regions of the legs, is lacking. In addition,

arm and neck cutouts are provided in the regions of the mannequin structure where the arms and neck, respectively, would normally be attached.

To use the above-described mannequin structure in photography applications, a unique costume arrangement, for example, a reproduction of a 1775 Revolutionary War British soldier's uniform, is constructed on the mannequin structure. The costume arrangement has an open, or "backless," portion between the shoulder and waist regions of the mannequin structure. A subject to be photographed stands behind the mannequin structure and partly "dresses" himself in the costume arrangement. In the case of the British soldier costume arrangement, the subject partly dresses himself therein by inserting his arms through the sleeves of the costume arrangement. The arm cutouts serve to facilitate this latter operation. The subject then leans forward slightly such that the upper part of his body, from essentially the shoulders to the waist, fits within the torso cavity of the mannequin structure and such that his neck is within the neck cutout and his chin is above and forward of the neck cutout. After assuming suitable positions for the arms and head, and after a few minor adjustments and additions to the costume arrangement, the subject is photographed by the photographer. In the final photographic print, the subject appears to be actually dressed in a full costume.

MANNEQUIN STRUCTURE

BACKGROUND OF THE INVENTION

The present invention relates to a three-dimensional structure for use by a photographer and, more particularly, to a three-dimensional mannequin structure having a costume arrangement disposed thereon for use in photography applications.

There are numerous occasions, for example, at historical sites, amusement parks, circuses, and sporting events, where it would be very desirable to be able to photograph a subject such that, in the final photographic print, the subject appears to be actually wearing the uniform or costume of a particular individual or figure, for example, the uniform of a 1775 Revolutionary War British soldier, the uniform of a professional hockey player, or the costume of a circus clown. While it would certainly be possible to actually dress the subject in a complete uniform or costume of the desired type, such a procedure would be inconvenient and unduly time consuming, thereby representing an uneconomical proposition for the photographer. Such well known arrangements as cardboard mockups having two-dimensional figures painted thereon and openings through which subjects place their heads to be photographed are generally undesirable because of the lack of authenticity in appearance of the two-dimensional painted figures in the final photographic prints produced from these arrangements.

The present invention serves to overcome the general problems and shortcomings associated with the abovedescribed techniques and arrangements.

SUMMARY OF THE INVENTION

Briefly, in accordance with the present invention, a three-dimensional structure is provided for use by a photographer in photographing a subject. In accordance with a preferred form of the invention, the three-dimensional structure is a three-dimensional mannequin structure which is similar in many respects to a conventional full-body mannequin as is commonly used for displaying wearing apparel. More specifically, the three-dimensional mannequin structure, like a conventional full-body mannequin, has a front torso portion and legs attached to the front torso portion. The mannequin structure, unlike a conventional full-body mannequin, lacks a head, neck, and arms, and further lacks a back portion from the region of the shoulders to a region below the waist, for example, to the region of the calves of the legs.

To employ the above-described mannequin structure in photography applications, a costume arrangement, including a wearable portion adapted to be worn by a subject while being photographed, is disposed on the mannequin structure. To be photographed, the subject places a portion of his body, for example, the portion of his body from the shoulders to the waist, within a cavity defined by front and side sections of the torso portion. At the same time, he wears the wearable portion of the costume arrangement. The subject, while positioned within the mannequin structure and the wearable portion of the costume arrangement as described above, is then photographed by the photographer.

BRIEF DESCRIPTION OF THE DRAWING

FIGS. 1(a), 1(b), and 1(c) are perspective, front, and back views, respectively, of a basic mannequin structure in accordance with a preferred form of the present invention prior to a costume arrangement being disposed thereon for use by a photographer;

FIGS. 2(a) and 2(b) are front and back views, respectively, of the basic mannequin structure shown in FIGS. 1(a)-1(c) after a costume arrangement, specifically, a costume arrangement representing a reproduction of a 1775 Revolutionary War British soldier's uniform, has been disposed thereon; and

FIG. 3 illustrates the general manner in which the mannequin structure and costume arrangement shown in FIGS. 2(a) and 2(b) may be used by a photographer in photographing a subject.

GENERAL DESCRIPTION OF BASIC MANNEQUIN STRUCTURE

FIGS. 1(a)-1(c)

Referring now to FIGS. 1(a), 1(b), and 1(c), there is shown in perspective, front, and rear views, respectively, a basic three-dimensional mannequin structure 1 in accordance with a preferred form of the present invention, that is, prior to a costume arrangement being disposed on the three-dimensional mannequin structure 1 for use by a photographer. As is readily apparent from FIGS. 1(a)-1(c), the mannequin structure 1, but for certain obvious and notable omissions, is similar to a conventional full-body adult-size mannequin as is commonly employed, for example, in department stores and clothing salons for displaying wearing apparel. More specifically, the basic mannequin structure 1 in accordance with the present invention includes the usual mannequin body parts of a front torso or trunk portion 2 (including chest, midsection, and hips), and legs 3 attached to the torso portion 2. The mannequin structure 1 differs most significantly from a conventional full-body mannequin in that it has no head, neck, or arms, and essentially the entire back, extending from the top of the shoulders, designated at 5 in FIGS. 1(a) and 1(c), to the calves of the legs 3, designated at 3a in FIGS. 1(a) and 1(c), is lacking. In addition to the abovementioned distinctions, a neck cutout 6 is preferably provided at the center of the top, front edge of the front torso portion 2, where a neck would ordinarily be attached, and arm cutouts 8 and 10 are preferably provided at the sides of the torso portion 2, where arms would ordinarily be attached. The purpose of the cutouts 6, 8, and 10 will be explained fully hereinafter in connection with FIG. 3.

In order to use the mannequin structure 1 for photography purposes, it is supported in an erect position. As indicated in FIGS. 1(a) and 1(c), this may be readily accomplished by means of a slightly curved rod 13 attached to the calf of one of the legs 3 (e.g., the calf of the right leg, as shown most clearly in FIGS. 1(a) and 1(c) and also to a support stand 12. This particular means for supporting the mannequin structure 1 is an erect position is conventional and well known to those skilled in the mannequin art.

MANNEQUIN STRUCTURE AND COSTUME ARRANGEMENT

FIGS. 2(a) and 2(b)

Before employing the above-described basic mannequin structure 1 in photographic applications for photographing subjects, a costume arrangement is first constructed on the mannequin structure 1. Any number of different costume arrangements may be used with the basic mannequin structure 1. However, for purposes of explaining the present invention, a particularly unique costume arrangement, representing a reproduction of a 1775 Revolutionary War British soldier's uniform, is shown at 15 in FIGS. 2(a) and 2(b). As shown in FIGS. 2(a) and 2(b), the British soldier costume arrangement 15 includes a coat 17, a vest 18, a jabot (or ruffle) 19, breeches (or pants) 20, stockings 21, and shoes 23. As may be noted from FIG. 2(b), the coat 17 and the underlying vest 18 are essentially "backless." As will become more fully apparent hereinafter, the purpose of the "backless" coat 17 and the "backless" vest 18 is to permit a subject who is to be photographed to readily place the upper part of his body, from essentially the shoulders to the waist, within the torso cavity of the mannequin structure 1. The "backless" coat 17 also permits subjects of different sizes to be accommodated in the torso cavity of the mannequin structure 1, as will also become more fully apparent. The torso cavity of the mannequin structure 1 is designated at 24 in FIG. 2(b) and also in FIGS. 1(a) and 1(c). To further insure that the costume arrangement 15 does not interfere with a subject placing the upper part of his body within the torso cavity 24 of the mannequin structure 1, the back part of the breeches 20 is conveniently attached to a portion of the mannequin structure 25 below the waist, for example, to the crotch of the mannequin structure 1, designated at 25 in FIGS. 1(a) and 1(c).

The component parts of the costume arrangement 15 may be disposed on the mannequin structure 1 in any suitable or desired manner. For example, the "backless" vest 18 may be attached, at its back edges, to the edges of the torso cavity 24, designated at 27 in FIGS. 1(a) and 1(c). The "backless" coat 17 may then be attached to the vest 18, for example, by pinning the inner lining of the coat 17 to the vest 18. With this arrangement, the top of the coat 17 is draped loosely over the shoulder regions 5 of the mannequin structure 1. The jabot 19, breeches 20, stocking 21, and shoes 23 are placed on the mannequin structure 1 in a conventional manner.

PHOTOGRAPHING A SUBJECT

FIG. 3

The manner in which the mannequin structure 1 and the costume arrangement 15 shown in FIGS. 2(a) and 2(b) may be used by a photographer in photographing a subject is indicated generally in FIG. 3. Initially, the subject to be photographed in the above-described arrangement stands behind the mannequin structure 1 with his feet placed close together and resting at least partially on the rear of the support stand 12. The shoulder portion of the "backless" coat 17 is then

removed from its draped position at the shoulder regions 5 of the mannequin structure 1 and the subject, with or without the assistance of the photographer or an assistant, partly "dresses" himself in the coat 17, more specifically, by placing his arms through the sleeves of the coat 17. The subject then leans forward slightly such that the upper part of his body, from essentially the shoulders to the waist, fits as snugly as possible within the torso cavity 24 of the mannequin structure 1 and such that his neck is within the neck cutout 6 and his chin is above and forward of the neck cutout 6. While the subject is in this position, the neck cutout 6 permits the subject to move his head and neck freely and naturally from side to side, and the arm cutouts 8 and 10 permit the subject to move his arms freely and naturally from side to side and also from front to back.

The subject then places his arms and head in suitable final positions for the photograph while, at the same time, the "backless" coat 17 is adjusted by the photographer or his assistant to provide a tight fit around the torso 2 of the mannequin structure 1 and also around the back of the subject. This latter operation may be readily accomplished by tying together laces attached to the back of the coat 17, for example, as shown at 17a and 17b in FIG. 2(b). As final preparatory steps to photographing the subject, a tricorn (three-cornered) or other hat may be placed on the head of the subject and suitable accessories to the costume arrangement 15, for example, a musket, may be placed in one of the hands of the subject, for example, as shown in FIG. 3. The subject, when finally positioned "within" the mannequin structure 1 and the costume arrangement 15 as described hereinabove, is then photographed by the photographer. In the event any portion of the legs or clothing of the subject are visible to the photographer when the subject is to be photographed, due to the open region between the legs 3 of the mannequin structure 1, an insert 32, generally of the same color as the background against which the photograph is to be taken and having a configuration generally conforming to the boundary of the open region, may be placed temporarily (or, if desired, permanently) in the region intermediate to the legs 3 of the mannequin structure 1. Of course, for other costume arrangements which may be used with the mannequin structure 1, for example, a full-length woman's dress, the insert 32 may not be necessary.

In the final photographic print produced as a result of photographing the subject in the above-described arrangement, the subject appears to be actually dressed in a full British soldier's uniform and not in portions of a few simple garments (i.e., a "backless" coat and a hat) as is actually the case. Thus, a photographic print is produced which is very realistic and authentic in appearance.

MODIFICATIONS

Although a mannequin structure has been described hereinabove which is of adult size, it is to be appreciated that mannequin structures of any size, including child-sized mannequin structures for use by children, may be achieved in accordance with the present invention. In addition, and as earlier mentioned, a variety of different types of costume arrangements, of a

male or female nature, may be used with mannequin structures in accordance with the present invention. It is also possible to construct a mannequin structure for use in the present invention in which the entire back half thereof, extending from the shoulders to the feet, is missing. In this case, a subject to be photographed may be able to position himself more snugly and completely within the mannequin structure. Other modifications and variations will be obvious to those skilled in the art without departing from the invention as called for in the appended claims. 10

What is claimed is:

1. An arrangement including:

A three-dimensional mannequin structure having a front torso portion and legs attached to the torso portion, and lacking a head, neck, and arms, said mannequin structure further lacking a back portion from the region of the shoulders to a region below the waist; and 15

means for supporting the mannequin structure in an erect position. 20

2. An arrangement in accordance with claim 1 wherein the region below the waist of the mannequin structure is the region of the calves of the legs. 25

3. An arrangement in accordance with claim 1 wherein the mannequin structure further has a cutout at the top edge of the front torso portion, and cutouts at the sides of the front torso portion. 30

4. An arrangement in accordance with claim 1 further including a costume arrangement disposed on the mannequin structure. 35

5. An arrangement in accordance with claim 4 wherein said costume arrangement has an open region at the back thereof between the region of the shoulders of the mannequin structure and the region of the waist of the mannequin structure. 40

6. An arrangement in accordance with claim 5 wherein said mannequin structure further has a cutout at the top edge of the front torso portion, and cutouts at the sides of the front torso portion. 45

7. An arrangement in accordance with claim 6 wherein the legs of the mannequin structure are spaced from each other and define an open region therebetween, said arrangement further including an insert positioned in the region intermediate to the legs of the mannequin structure and having a configuration generally conforming to the boundary of said region. 50

8. An arrangement for use by a photographer in photographing a subject, comprising:

a three-dimensional structure having a cavity formed therein for receiving and partially enclosing a portion of the body of the subject; and 55

a costume arrangement disposed on the three-dimensional structure, said costume arrangement including a portion adapted to be worn by the subject while the subject has the said portion of his body within the cavity in the three-dimensional structure.

9. An arrangement in accordance with claim 8 wherein the costume arrangement has an open region therein adjacent to the cavity in the three-dimensional structure, said open region permitting the subject to place the said portion of his body within the cavity in the three-dimensional structure. 5

10. An arrangement for use by a photographer in photographing a subject, comprising:

a three-dimensional mannequin structure having a front torso portion and legs attached to said front torso portion, said front torso portion having a front section and side sections defining a torso cavity, said mannequin structure lacking a head, neck, and arms, and further lacking a back portion from the region of the shoulders to a region below the waist, said mannequin structure further having a neck cutout at the top edge of the front section of the front torso portion and arm cutouts at the side sections of the front torso portion; means for supporting the mannequin structure in an erect position; and

a costume arrangement disposed on the mannequin structure, said costume arrangement having an open region at the back thereof adjacent the torso cavity of the mannequin structure, said open region at the back of the costume arrangement permitting the subject to be photographed to place the upper part of his body, from essentially the shoulders to the waist, within the torso cavity of the mannequin structure, and said costume arrangement including a wearable portion adapted to be worn by the subject while he has the upper part of his body within the torso cavity of the mannequin structure;

said neck cutout permitting the subject to move his head and neck freely and naturally and said arm cutouts permitting the subject to move his arms freely and naturally while he has the upper part of his body within the torso cavity of the mannequin structure and he is wearing the wearable portion of the costume arrangement.

11. An arrangement in accordance with claim 10 wherein the region of the mannequin structure below the waist is the region of the calves of the legs. 45

12. An arrangement in accordance with claim 10 wherein the costume arrangement includes a garment having an open region at the back thereof adjacent the torso cavity of the mannequin structure and including sleeves, said wearable portion including said sleeves. 50

13. An arrangement in accordance with claim 12 wherein said garment is a coat.

14. An arrangement in accordance with claim 10 wherein the legs of the mannequin structure are spaced from each other and define an open region therebetween, said arrangement further including an insert positioned in the region intermediate to the legs of the mannequin structure and having a configuration essentially conforming to the boundary of said region. 55
